GEORGE A. GILLEN, OF JERSEY CITY, NEW JERSEY, ASSIGNOR TO GILLEN, KIMMEY, BAKER, SYNDICATE INC., OF NEW YORK, N. Y.

VACUUMIZER

Application filed December 18, 1923. Serial No. 681,326.

This invention relates to improvements in vacuumizers and is primarily designed for use in sealing cans, jars and the like ordinarily used in preserving, it being well recognized that the keeping quality of the contents of any vessel are much improved through the creation of at least a partial vacuum within the container.

Another object of the invention resides in the provision of a device so designed that one or more jars may be sealed simultaneously and with but a single operation of the device.

As a further object the invention contemplates the provision of an improved packing between the moving elements which will effectively prevent the escape of air between the moving parts thereby insuring maximum efficiency.

With these and other objects in view which will become more apparent as the description proceeds the invention consists in the novel construction, combination and arrangement of parts which will be fully set forth in the following specification, claimed and illustrated in the accompanying drawing, in which:—

Figure 1 is a top plan view partially in section of this improved vacuumizer showing the same constructed for household use.

Figure 2 is a side view of Figure 1 showing portions broken away to clearly illustrate the details of construction.

Figure 3 is a fragmentary enlarged sectional view illustrating the packing in detail.

Figure 4 is an enlarged fragmentary view of a portion of the device illustrating a modified form of valve.

Figure 5 is a view similar to Figure 2 of a modified form of vacuumizer showing the same constructed for handling a multiplicity of cans, and

Figure 6 is an enlarged fragmentary sectional view of Figure 5 showing the packing used in connection therewith.

Referring to the drawings in detail the numeral 10 designates in its entirety the body of the device which comprises a base 11 having secured to its upper side an outer cylindrical wall 12. An inner cylindrical wall 13 is secured to said base in spaced parallel rela-

tion thereto to provide the inner and outer chambers 14 and 15 respectively. The wall 13 is provided with an opening 16 and a similar opening 17 is formed in the wall 12 for a purpose to be more fully hereinafter described.

Secured to the wall 13 above the opening 16 is a strip 18 which retains a flap valve 19 in place on the wall 13 where it will act to close the opening 16. A similar strip 20 retaining the flap valve 21 in place over the opening 17 is secured to the wall 12 and thus it will be seen that the flow of air through the openings is checked in one direction.

Co-operating with the body 10 is the head 65 designated generically by the numeral 22 which comprises a top or cover member 23 to the underside of which is secured an open ended cylinder 24 of a diameter to readily fit into the chamber 15 as clearly shown in Figs. 60 1 and 2. A handle 25 is secured to the upper side of the cover 23 for an obvious purpose.

Formed at the lower end of the cylinder 24 are flanges 26 serving as a base or support for the packing rings 27 and 28 which are arranged so that their right portions abut and are secured in place by a retaining ring 29. In order to yieldably hold the packing rings 75 27 and 28 in proper position I also provide the inner and outer bands 30 and 31 respectively, 70 of a relatively soft compressible material such as rubber. As shown these rings 30 and 31 are substantially triangular in cross section.

In the modified form of valve illustrated in Figure 4 the opening 32 is perfectly tapered 85 to receive the cone shaped portion 33 of a flap valve 34 which is hinged as at 35 to the wall of its respective chamber.

In the modified form of the device illustrated in Figure 5 the body designated 90 generically by the numeral 36 comprises a bottom 37 which is secured at its edge within an annular wall 38. This bottom is provided with an opening 39 which is normally covered by a flap valve 40 which is retained in place 95 by means of a strip 41. Arranged to fit within the body 36 is the head member designated generically by the numeral 42 which comprises a container consisting of the side and bottom walls 43 and 44 respectively and a 100

removable cover 45 which is retained in place by means of clamps 46 and rendered airtight through the use of a gasket 47 interposed between the cover and the upper edge of the wall 43.

5 Like the bottom wall of the body 36 the bottom wall 44 of the container is provided with an opening 48 which is covered by a flap or check valve 49 secured in place by means of a strip 50.

10 As illustrated in Figure 6 the wall 44 is extended beyond the outer face of the wall 43 to provide a flange 51 for supporting the packing ring 52. A retaining ring 53 is secured to the device in such a position as to firmly clamp the packing ring in place.

15 In the operation of the structure illustrated in Figures 1, 2 and 3 the preserving jar designated by the numeral 54 is seated on the bottom 11 within the chamber 14. The head 22 is then pressed downwardly thus causing the air contained within the chambers 13 and 14 to be exhausted and displaced with the air contained within the head. Upon upward 20 movement of the head it will be obvious that the valves 19 and 21 will effectively close the openings 16 and 17 so as to create a partial vacuum within the chambers and upon continued upward movement and rapid removal 25 of the head from the body it will be apparent that the sudden external pressure on the jar 54 will cause the lid to tightly seat on the usual rubber gasket. Thus it will be seen that a partial vacuum will be created within 30 the jar 54 which will facilitate the keeping of the contents against spoilage.

35 The operation of the device illustrated in Figure 5 is essentially that previously described with the exception that the jars are placed within the head 42 and the cover 45 is removably attached for the purpose of rendering access to the interior of the head member easy.

40 While in the foregoing there has been shown and described the preferred embodiment of this invention it is to be understood that minor changes and details of construction, combination and arrangement of parts 45 may be resorted to without departing from the spirit and scope of the invention as claimed.

50 What is claimed is:—

55 1. A vacuumizer comprising hollow telescopic members, operating one within the other and having walls forming an inner vacuumizing chamber of variable capacity and an outer variable capacity vacuumizing space, outwardly opening valve 60 means from said vacuumizing space to the outer air, outwardly opening valve means from the vacuumizing chamber to said vacuumizing space, packing between adjacent walls of the relatively movable members and 65 means by which the members may be relative-

ly shifted to effect the vacuumizing operation.

2. A vacuumizer comprising separable open-ended hollow telescopically related members, one being a double wall structure providing an annular space, and the other member operating as a piston in said annular space, the space within the inner-most wall of the double wall structure forming a vacuumizing chamber and the annular chamber with the piston wall operating therein forming a chamber of variable capacity interposed between the outer air and the inner vacuumizing chamber, valve means on the double wall structure between said intermediate chamber and the vacuumizing space, and between the intermediate chamber and outer air to permit escape of air when the members are relatively shifted in one direction, packing between the piston wall and the double wall structure to prevent return of air when the members are forced in the opposite direction.
